US00D610430S

(12) **United States Design Patent**
Fritz et al.

(10) **Patent No.:** **US D610,430 S**
(45) **Date of Patent:** **** Feb. 23, 2010**

(54) **STEM FOR A POWER TOOL ATTACHMENT**

(75) Inventors: **Peter J. Fritz**, Minneapolis, MN (US); **Nathan A. Abel**, Minneapolis, MN (US); **Matthew D. Chaffee**, White Bear Lake, MN (US); **Michael J. Annen**, Hudson, WI (US); **Peter A. Felipe, Sr.**, St. Paul, MN (US); **Adam M. Spah**, Blaine, MN (US); **Wesley A. Raider**, Hudson, WI (US)

FIG. 1 is a perspective view of a power tool attachment showing the new design for a stem for a power tool attachment;

FIG. 2 is a right side view thereof;

FIG. 3 is a front view thereof;

FIG. 4 is a left side view thereof;

FIG. 5 is a back view thereof;

FIG. 6 is a bottom view thereof; and,

FIG. 7 is a top view thereof.

The broken line showing of structural features is included for the purpose of illustrating non-claimed subject matter and forms no part of the claimed design.
